UNITED STATES PATENT OFFICE

GEORGE L. DANFORTH, JR., OF CHICAGO, ILLINOIS, ASSIGNOR, BY MESNE ASSIGNMENTS, TO OPEN HEARTH COMBUSTION COMPANY, OF CHICAGO, ILLINOIS, A CORPORATION OF DELAWARE

FURNACE

Application filed January 28, 1922. Serial No. 532,441.

This invention relates to a new and improved furnace and more particularly to an improved construction of ports and passages in connection with reversible regenerative furnaces.

As is well known in the art, reversible regenerative furnaces, such as open hearth steel furnaces, are provided with similar ends and the ports and passages upon opposite ends serve alternately to introduce the air and fuel and to conduct away the products of combustion. Since the products of combustion exceed in volume the entering air and fuel, it is necessary to provide ports and passages of an area adapted to carry off the products of combustion. Ports of this necessary area do not adequately direct and control the incoming air and gases and hence do not provide the most efficient working flame. Furthermore, the design of a port for introduction of gases is of necessity different from that most desirable for carrying off gases in the opposite direction.

Various constructions, such as that shown in the patent to McKune, No. 1,339,855, dated May 11, 1920, have been designed whereby additional passages are provided upon the outgoing end, these passages being closed by dampers upon the incoming end.

According to the present invention, the air uptakes, which also serve as downtakes to carry off the products of combustion, are provided with dampers adjacent their point of junction with the furnace proper. The present furnace is adapted for use with liquid or gaseous fuels which are not preheated and supplemental passages are provided connecting the uptakes at a point below the dampers to the fuel introduction port.

It is an object of the present invention to provide a furnace construction such that adequate port area is provided for carrying off the products of combustion and such that the incoming air is properly directed to produce an efficient working flame.

It is a further object to provide a construction of this character in which spaced ports of relatively great area are provided for carrying off the products of combustion and in which a port of comparatively small

area is provided for introducing the air and fuel.

It is an additional object to provide a construction which is simple in design and which may be applied to existing installations without material alteration thereof.

Other and further objects will appear as the description proceeds.

I have illustrated a particular embodiment of my invention in the accompanying drawings, in which—

Figure 1 is a vertical section showing an end of the furnace constructed according to my invention.

Figure 2 is a horizontal section, partly broken away; and

Figure 3 is a transverse vertical section through the furnace end.

As shown in the drawings, the furnace chamber 4 is provided at either end with the spaced discharge ports 5 which lead downwardly adjacent the end walls 6 of the furnace. Outwardly inclined passages 7 which serve both as uptakes and downtakes lead from these ports to the slag pocket 8, the upper portion of the slag pocket being directly connected to the checker chambers 9. The horizontal dampers 10 are located adjacent the upper ends of the uptakes. As shown these dampers are horizontally movable by means of the shaft 11 which is provided with gears 12 meshing in racks 13 connected to the dampers.

Supplementary passages 14 lead from the uptakes 7 at points below the dampers 10 and these passages extend horizontally at 15 and together join to form the passage 16 leading to the entrance port 17. This entrance port 17 is directed through the water-cooled opening 18 in the furnace end wall. It will be observed from Figure 2 that the entrance port 17 is directed intermediate the two discharge ports 5. The nozzle 19 is introduced through the rear of the port and serves to introduce the fuel.

Upon the incoming end of the furnace, the dampers 10 close off the discharge ports 5. The preheated air comes through the checker damper 9 and up the uptakes 7 and thence through the supplemental pas-

sages 14 to the port 17. The fuel is introduced through nozzle 19. This entrance port 17 serves to adequately direct and control the incoming air and fuel and an efficient flame may be maintained.

Upon the outgoing end, the dampers 10 are drawn outwardly and the products of combustion may pass directly through the ports 5 and thence down the uptakes 7 and out 10 through the checker chamber. Thus an adequate area is provided for the products of combustion and these are readily conducted away without the necessity for forced draft means. Further, the wear upon the entrance 15 port 17 due to the erosion caused by heated outgoing gases is materially reduced.

The form of construction shown is illustrative only and it is my intention to cover all modifications coming within the spirit 20 and scope of the appended claims.

I claim:

1. In a regenerative furnace, a pair of uptakes connecting the regenerators and the furnace chamber at each end thereof, the 25 uptakes terminating in spaced ports in the furnace floor, and an incoming fuel and air port extending through the furnace wall intermediate the spaced ports, said fuel and air ports being independent of the furnace 30 walls.

2. In a regenerative furnace, a pair of uptakes connecting the regenerators and the furnace chamber at each end thereof, the uptakes terminating in spaced ports in the 35 furnace floor, an incoming fuel and air port directed intermediate the spaced ports, and supplementary passages connecting the uptakes and the fuel and air port.

3. In a regenerative furnace, a pair of 40 uptakes connecting the regenerators and the furnace chamber at each end thereof, the uptakes terminating in spaced ports in the furnace floor, an incoming fuel and air port directed intermediate the spaced ports, sup- 45 plementary passages connecting the uptakes and the fuel and air port, and dampers located in said uptakes above the junctions of the supplementary passages with the uptakes.

50 4. In a regenerative furnace, furnace ends having uptakes terminating in the floor of the ends, each end being unobstructed between the termination of the uptakes therein, and a port in the end wall of the furnace 55 terminating between the uptakes.

5. In a regenerative furnace, furnace ends having uptakes terminating in the floor of the ends, each end being unobstructed between the termination of the uptakes therein, 60 dampers in said uptakes, and a port in the end wall of the furnace terminating between the uptakes.

6. In a regenerative furnace, furnace ends having uptakes terminating in the floor of 65 the ends, each end being unobstructed be-

tween the termination of the uptakes therein, a port in the end wall of the furnace terminating between the uptakes, and additional passages connecting the uptakes and the ports.

7. In a regenerative furnace, furnace ends having uptakes terminating in the floor of the ends, each end being unobstructed between the termination of the uptakes therein, dampers in said uptakes, a port in the end 75 wall of the furnace terminating between the uptakes, and additional passages connecting the uptakes below the dampers with the end wall port.

Signed at Chicago, Illinois, this 21st day 80 of January, 1922.

GEORGE L. DANFORTH, JR.
